UNITED STATES PATENT OFFICE.

ALFRED T. NEWELL, OF BIRMINGHAM, ALABAMA.

RAILWAY-TRACK PAVING.

1,407,436.

Specification of Letters Patent. Patented Feb. 21, 1922.

Application filed December 16, 1921. Serial No. 522,806.

To all whom it may concern:

Be it known that I, ALFRED T. NEWELL, a citizen of the United States, residing at Birmingham, in the county of Jefferson 5 and State of Alabama, have invented certain new and useful Improvements in Railway-Track Paving, of which the following is a specification.

This invention relates to paving between car tracks, and has for its object to provide a construction which will obviate many of the objections incident to paving between or along railway tracks.

It is well known that paving along rail- 15 ways is subject to considerable vibration which results in cracking or disintegration of the paving, in consequence of which frequent repairs are necessary. This is a matter of observation in street railway installations, and the maintenance of such paving forms a large item in street railway or city expense. The injurious effects of street railway traffic on asphalt and concrete pavement is so well recognized that bricks are usually 20 employed for this purpose, the bricks being laid between the tracks and for about a foot and a half outside of the tracks. These bricks make numerous joints and vibration causes them to settle in spots, producing 25 generally unsatisfactory conditions.

My invention remedies these conditions, and provides means for producing a substantially continuous paving between tracks, in such manner that it will not be subject 35 to crack or disintegration in consequence of vibration, and a smooth and highly efficient pavement results.

One form of the invention is illustrated in the accompanying drawings in which 40 Fig. 1 is a plan of such a paving. Fig. 2 is a cross section thereof. Fig. 3 is a detail in section on the line 3-3 of Fig. 1.

In the drawings, 6 indicate the rails of street car or other tracks. These are set 45 on ties, usually wooden, indicated at 7, in the ordinary manner. To construct my paving between and along the rails I first provide a series of concrete sills or blocks indicated at 8, which are set at suitable 50 spaces apart say four or six feet, in the road bed under the rails. Each sill preferably extends half way across the track, being joined at the middle, as by means of reinforcement loops 9 and ties 10 uniting 55 said loops at the corners of the blocks. Each block has a cross recess or depression indi-

cated at 11, into which the base of the rail extends, but, preferably, the rails do not rest on these blocks, but are spaced therefrom slightly, as indicated at 12, so that 60 the blocks are not subject to the direct vibration or pressure of the rails, the rails being supported by the ordinary ties. And these blocks 8 are set in the road bed with their tops flush with the central depression of the road bed which receives the paving surfacing. 65

This surfacing consists of a plurality of slabs 13. Each slab is of a width equal to the space between the rails for the inside 70 location, and for the outside location similar slabs 14 are used, usually a foot and a half wide to meet the established paving indicated at 15. The slabs may be as long as desired, but correspond in length to the 75 distance apart of the center lines of the blocks 8, and these slabs are laid between and beside the rails so that they meet above the foundation blocks 8 and rest thereon, as well as on the intermediate ballast or 80 road bed. The slabs are a proper thickness to bring them flush to the face of the rail, and the central slabs are grooved as indicated at 16 for the wheel flanges.

The slabs may be reinforced with metal 85 rods or the like, and each slab is cut off at the corners to form a recess as indicated at 17, and one of the reinforcing rods 18 is exposed in the form of a loop 19 at said recess. Each block 8 is provided with a 90 metal eye 20 cast therein, in proper position to register with said recesses when the slabs are laid together on the blocks, and then the loops 19 of the adjacent slabs and the loops 20 of the underlying blocks are tied 95 together by a metal wire tie 21, thus firmly uniting the slabs to each other, and both to the blocks. Grout or liquid cement may then be poured in the recesses to fill the same. Or tar may be poured in, and preferably I 100 use tar to pour in the cracks between the rails and the slabs, this tar flowing down through said cracks and around the base of the rail, where it may fill the spaces 12. The whole forms a water tight paving and 105 prevents the leakage of water through the same into the space under the slabs. Tar is also poured in the cross joints between the slabs.

The slabs may be cast in large numbers 110 in a central plant, and transported to the place where they are laid, and when laid

a substantially solid paving will be produced. The tar joints will tend to take up vibration, and in any event, the slabs being properly cured, they will not be subject to cracking or dislocation incident to vibration, and will be free from the necessity of repair, making them superior to the ordinary means used for paving between tracks.

10. The invention is not limited to the particular form and proportions shown, but may be varied in many ways within the scope of the following claims.

I claim:

15. 1. A paving for car tracks, comprising a series of spaced blocks set in the road bed under the track rails, said blocks being independent of the track ties and spaced below the rails and a succession of pre-formed 20 concrete slabs set beside or between the rails and resting on said blocks.

2. A paving for car tracks, comprising a plurality of blocks extending across the road bed under the rails, said blocks being spaced 25 apart along the track, and spaced below the rails and independent of the ties, and a plurality of pre-formed concrete slabs fitting between the rails and resting at their meeting edges upon said blocks.

30. 3. A paving for car tracks, comprising a plurality of blocks extending across the road bed under the rails, said blocks being spaced apart along the track, and a plurality of

pre-formed concrete slabs fitting between the rails and resting at their meeting edges upon 35 said blocks, said slabs having recesses at their edges and reinforcing members exposed at said recesses, and fastenings connecting the blocks and said exposed members. 40

4. A paving for car tracks comprising a series of spaced blocks extending crosswise of the track and located under the rails, said blocks being spaced downward below the rails, and a succession of concrete slabs 45 laid beside the rails and resting at their ends on said blocks.

5. The combination with a track rail mounted on ties, of a paving comprising a series of spaced blocks independent of and 50 set between the ties and spaced below the rails, and a succession of pre-formed concrete slabs set beside the rails and resting at their ends upon said blocks. 55

6. The combination with a track rail mounted on ties, of a paving comprising a series of spaced blocks set between the ties and under the rails, and a succession of pre-formed concrete slabs set beside the rails and resting at their ends upon said blocks, 60 said slabs having recesses at their meeting edges, and reinforcements exposed at said recesses, and fastenings connecting the blocks and said exposed reinforcements.

In testimony whereof, I affix my signature. 65

ALFRED T. NEWELL.
